SPOON OR SIMILAR ARTICLE

Ellen B. Manderfield, Syracuse, N.Y., assignor to Oneida Ltd., Oneida, N.Y.

Filed Aug. 31, 1973, Ser. No. 393,655

Term of patent 14 years

Int. Cl. D7—03

U.S. Cl. D7—150

FIG. 1

FIG. 2

FIG. 3

FIG. 6

FIG. 4

FIG. 5

FIG. 1 is a front view of a spoon showing my new design;

FIG. 2 is a rear view thereof;

FIG. 3 is a side view thereof, the undisclosed side being substantially identical with the side shown in FIG. 3;

FIG. 4 is an enlarged cross-section taken on line 4—4 of FIG. 1;

FIG. 5 is an enlarged cross-section taken on line 5—5 of FIG. 1; and

FIG. 6 is a fragmentary enlarged view of a portion of my design disposed between the upper end of the spoon and line 4—4 of FIG. 1.

I claim:

The ornamental design for a spoon or similar article, substantially as shown and described.
